UNITED STATES PATENT OFFICE.

MAX J. STRASBERGER, OF CHICAGO, ILLINOIS.

SIGNAL LAMP.

Application filed May 23, 1921. Serial No. 471,816.

To all whom it may concern:

Be it known that I, MAX J. STRASBERGER, a citizen of the United States, residing at Chicago, in the county of Cook and State 5 of Illinois, have invented certain new and useful Improvements in Signal Lamps, of which the following is a specification.

The present invention has to do with an improved form of signal, but has reference 10 more particularly to electrically lighted signals. The important object of the invention is to provide a signal by which may be given an indication of one or more units as desired by the operator.

15 The signal of the present invention is especially intended for use in theaters and moving picture houses. When used in such places, the signal is so constructed that the user can indicate the number of vacant seats 20 available at a certain point.

Another object of the invention is to provide a signal of this kind which is so constructed that the indication of the number of seats is given by illuminating the correct 25 number of lamps therein, as distinguished from an arrangement in which the indication is given by the display of a certain numeral. This distinction will be better appreciated when it is considered that it is 30 much easier to clearly make out the number of separate illuminating units burning at a distance than it is to read a numeral with accuracy at the same distance unless said numeral be so large as to be inconvenient 35 for use in a relatively small signal.

Another object of the invention is to simplify the construction of the switch elements and provide a construction which shall be very durable and at the same time 40 cheap to manufacture. Another object is to provide a shell for the battery which shall be so constructed that the battery may be very easily inserted or removed for replacement or otherwise.

45 Other objects and uses of the invention will appear from a detailed description of the same, which consists in the features of construction, and combinations of parts hereinafter described and claimed.

50 Referring to the drawing:

Figure 1 shows a front face view of a signal embodying the features of the present invention, the interior switch and associated parts being shown by dotted lines;

55 Fig. 2 shows an edge view corresponding

to Figure 1 and looking towards the hinged edge;

Fig. 3 shows a back face view corresponding to Figures 1 and 2;

Fig. 4 shows a top view;

Fig. 5 shows an edge view looking in the opposite direction to Fig. 2;

Fig. 6 shows a bottom view;

Fig. 7 shows a fragmentary vertical section through one of the switch units being 60 taken on line 7-7 of Fig. 1, looking in the direction of the arrows, and on an enlarged scale;

Fig. 8 shows a perspective view of a portion of the double switch unit; and

Fig. 9 shows a perspective view of a portion of the single switch unit.

The signal herein illustrated includes a case 10, the body portion of which is split into two parts, which are hinged together 75 along the edge 11. These two parts are split along the bottom of the case, as shown in Fig. 6, and up the other edge, as shown in Fig. 5, and across on the back face near the top, as shown at 12 in Fig. 3. The top portion 13 of the case is integral with the front face 14, so that when the back face 15 is opened away from the front face on the hinge 11, the top portion 13 remains stationary with respect to the front face 14.

80 A battery or electric cell 16 is set into the body portion of the case and has one terminal 16^a grounded on or connected to the case itself. The other terminal of the battery connects to a crosswise extending bus 90 bar 17.

85 In the upper portion 13 of the case there are mounted a number of lighting elements 18, 19, 20 and 21, each of which comprises a small electric lamp screwed into a socket in the upper portion 13, so that one terminal of each lighting element is directly connected to the case itself and therefore to one terminal of the battery.

95 Suitable switches are provided for illuminating one, two or three of the lighting elements simultaneously, so that the user can give a corresponding indication of the number of seats available. These switches are manipulated by buttons 22 and 23. The button 22 operates a single switch to illuminate the element 18; the button 23 operates a double switch to illuminate the elements 19 and 20; and when both of the buttons are manipulated together all three of the elements 110

18, 19 and 20 are simultaneously illuminated.

Each of the switches includes a vertical U-shaped member 24 having the upper and lower horizontal arms 25 and 26. These members are raised and lowered by the operation of the buttons, and when fully raised the arm 25 strikes the central contact 27 of the corresponding lighting element, the lower arm 26 striking the bus bar 17 at the same time. The U-shaped members 24 are made of flexible electrically conducting material so that the proper contacts will be insured.

15 The single switch includes a sidewise protecting arm 28, one end 29 of which is folded around the central portion of the corresponding member 24, from which it is insulated, however, by an insulating sleeve 30. Said arm 28 has an end opening 31 which receives the neck 32 of the corresponding switch button, which switch button is riveted thereto, as shown at 33. The double switch includes a cross bar 34, whose end portions 35 and 36 are folded around the central parts of the corresponding switch members 24, from which they are insulated by the insulating sleeves 37 and 38. In the middle of the cross bar 34 is an opening 39 which receives the neck of the button 23 which is riveted thereto in a manner similar to that shown in Fig. 7.

In order to automatically restore the switch elements to the open circuit position, 35 each of them is normally pressed downwardly by means of a spring 40. The inner end 41 of such spring is secured to the case 10 and its free end 42 is forked and engages the neck of the corresponding switch button. 40 These forks are clearly illustrated by the dotted lines in Fig. 1. Sufficient flexibility is provided in the springs to permit them to be easily manipulated by a finger on the switch button.

45 I have illustrated a fourth lighting element 21 in the present drawing. This lighting element when used may be controlled by a button 43 which operates a switch similar in construction to those already explained.

50 This fourth lighting element may be used either in conjunction with the other three or separately. Ordinarily it will be desirable to provide it with a bright lamp which may be used as a spot light. The lighting elements 18, 19 and 20 will ordinarily burn relatively dim so as not to distract the attention of the patrons of the show. They may furthermore be colored either the same or different colors so as to further emphasize the indicating of the number of seats.

60 The hinged leaf 15 of the case may be locked shut in any desired manner, as, for example, by the clips 44 shown in the different figures.

65 While I have herein shown and described

a construction in which there are provided three lighting units which may be illuminated in combinations of either one, two or three, and is also provided with another lighting unit which may be used independently, 70 still it will be understood that I do not limit myself to this or any other number of lighting units except as I may do so in the claims.

75 While I have herein shown and described only a single embodiment of the features of the present invention, still I do not limit myself to said embodiment except as I may do so in the claims.

I claim:

1. A signal for the purpose specified, comprising a relatively thin case having in its upper end a series of sockets for the reception of electric lighting elements having central contacts, said sockets being grounded on the case, said case having its lower portion split and hinged whereby one side of said lower portion may be opened, an electric battery within said split portion of the case having one of its terminals grounded on the case, a bus bar connected to the other terminal of the battery and extending across the case parallel to the upper end of the battery, and a series of switch units located between said bus bar and the central contacts of the electric lighting elements, each switch unit including a button slidably mounted in one face of the case at a point between the bus bar and the lighting elements, a U-shaped flexible member of conducting material, an operating electrical insulating connection between each button and the corresponding U-shaped member, the arms of the U-shaped member lying respectively below the bus bar and below the central contact of the corresponding lighting element, and a spring having one end connected to the casing and its other end working in conjunction with one of the switch buttons to normally depress the same and thereby carry the arms of the U-shaped member away from the contact of the lighting element and the bus bar respectively, substantially as described. 100

105 2. A signal for the purpose specified, comprising a case having in its upper end a series of sockets for the reception of electric lighting elements having central contacts, said sockets being grounded on the case, said case having its lower portion split and hinged whereby one side of said lower portion may be opened, an electric battery within said split portion of the case having one of its terminals grounded on the case, a bus bar connected to the other terminal of the battery and extending across the case parallel to the upper end of the battery, and a series of switch units located between said bus bar and the central contacts of the electric lighting elements, each switch unit including a button slidably mounted in one face of the case, a U-shaped flexible member 110

115

120

125

130

of conducting material, and an operating electrical insulating connection between each button and the corresponding U-shaped member, the arms of the U-shaped member lying respectively below the bus bar and below the central contact of the corresponding lighting element, substantially as described.

3. A signal for the purpose specified, comprising a case having in its upper end a series of sockets for the reception of electric lighting elements having central contacts, said sockets being grounded on the case, said case having its lower portion split and hinged whereby one side of said lower portion may be opened, an electric battery within said split portion of the case having one of its terminals grounded on the case, a bus bar connected to the other terminal of the battery and extending across the case parallel to the upper end of the battery, and a series of switch units located between said

bus bar and the central contacts of the electric lighting elements, said switch units serving selectively to effect contact with the central contacts of the selected lighting elements as desired, substantially as described.

4. A signal for the purpose specified, comprising a case having in its upper portion a series of sockets for the reception of electric lighting elements having central contacts, said sockets being grounded on the case, an electric battery within the lower portion of the case having one of its terminals grounded on the case, a bus bar connected to the other terminal of the battery and extending across the case parallel to the upper end of the battery, and a series of switch units in one side of the case serving to selectively effect connection between said bus bar and the central contacts of the electric lighting elements, substantially as described.

MAX J. STRASBERGER.
